COMBINED READER AND SORTER FOR MAGNETIC INSCRIBED DOCUMENTS

Edward J. Sabella, Raleigh, N.C., assignor to International
Business Machines Corporation, Armonk, N.Y., a cor-
poration of New York

Filed Aug. 30, 1966, Ser. No. 3,649

Term of patent 14 years

(Cl. D26—5)

FIG. 1

FIG. 2

FIG. 3

FIG. 4

FIG. 5

FIG. 6

FIG. 1 is a front perspective view of a combined reader and sorter for magnetic inscribed documents, showing my new design.

FIG. 2 is a front elevation view of the same.

FIG. 3 is a top view of the same.

FIG. 4 is a rear view of the same.

FIG. 5 is a left side view of the same.

FIG. 6 is a right side view of the same.

The dominant features of my design reside in those portions shown in full lines on the drawing.

I claim:

The ornamental design for a combined reader and

sorter for magnetic inscribed documents, as shown and described.
